UNITED STATES PATENT OFFICE

2,475,728

COLLISION SWITCH

Walter M. Smith, San Diego, Calif.

Application December 31, 1946, Serial No. 719,576

1 Claim. (Cl. 200—52)

1

This invention relates to improvements in electric switches for shutting off the motive power of a motor vehicle in case the latter collides with an object or another vehicle.

The primary object of the invention is to provide means for reducing the fire hazard resulting from the participation in a collision of a motor vehicle driven by an internal combustion engine which uses highly volatile or explosive fuels. The invention will also prevent or discourage "hit and run" driving after collisions.

Specifically, the invention contemplates provision of a safety switch adapted to automatically break the ignition circuit of the motor vehicle engine upon the occurrence of a collision, the switch being extremely simple in construction and highly efficient in operation.

The exact nature of the present invention will become apparent from the following description and considered in connection with the accompanying drawing, in which:

Figure 1 is a bottom plan view of a collision switch constructed in accordance with the present invention.

Figure 2 is a central vertical sectional view of the switch shown in Figure 1, taken on the plane of line 2—2 of Figure 1.

Figure 3 is a horizontal section taken on line 3—3 of Figure 2.

Referring in detail to the drawing, the present switch includes a closure cap 5 having a lateral horizontal flange 6 which is apertured as at 7 to facilitate bolting of the switch to a motor vehicle. An inverted cup-shaped casing 8 has its lower end removably screwed or secured in the closure cap 5, and a central binding post 9 is fixedly secured to and extends through the top wall of casing 8. This binding post includes a screw 10 which extends through an aperture in the top wall of casing 8 and is drawn tight by a nut 11 threaded thereon. A second nut 12 is threaded on the bolt 10 and coacts with the nut 11 for securing the terminal connection 13 of a conductor wire 14 to the binding post. A second central binding post 15 is fixedly secured to and extends through the closure cap 5, and this binding post 15 includes a bolt 16 passed through an aperture of the cap 5 and having an inner contact head 17 formed at the top with a concave seat 18. A nut 19 is threaded on the bolt 16 to draw the same tight, and a second nut 20 is threaded on said bolt 16 and coacts with the nut 19 to secure the terminal connection 21 of a second conductor 22 to said binding post 15. In practice, the wire 22 is connected to a terminal of the vehicle battery, and

2

the wire 14 is connected to the ignition coil so that the present switch is interposed or installed between the battery and the coil.

A solid metallic conducting ball 23 is arranged in the casing 8 and is adapted to rest in the seat 18. A helical contact spring 24 is arranged in the casing 8 and is attached at its upper end to the binding post 9 so that the lower end of said spring is arranged to bear upon the ball 23 and thereby yieldingly hold the latter in the seat 18. In this way, an electrical connection is normally provided between the binding posts 9 and 15 so as to close the ignition circuit until the ball 23 is jarred from between the contact head 17 and the contact spring 24 by violent impact of the vehicle with an object or another vehicle. As soon as the latter occurs, the electrical connection between the binding posts 9 and 15 is broken so that the ignition circuit of the vehicle engine is opened for throwing the engine out of operation. As shown, a split washer 25 is placed on the bolt 10 within casing 8 and on the head of said bolt, and the upper end of spring 24 is extended through and above the washer 25 so that when the nut 11 is tightened, the upper end of the spring 24 is securely attached to the binding post 9.

The present switch may be mounted on the vehicle so that it is difficult of access, thereby delaying resetting of the switch following a collision, which resetting requires removal of the casing 8 from the cap 5 and replacement of the ball 23 in the seat 18, as well as replacement of the casing 8 with respect to the cap 5. It will be apparent that the present switch prevents the electric current of the ignition system of the vehicle engine from igniting fuel which may splash or leak as a result of the collision.

The present switch is extremely simple in construction, economical to manufacture, and easy to install and use.

What I claim is:

A collision switch including a bottom closure cap having means to facilitate attachment thereof to a motor vehicle, an inverted cup-shaped casing having its lower end removably secured in said closure cap, a central binding post fixedly secured to and extending through the top wall of said casing, a second central binding post fixedly secured to and extending through the closure cap and having an inner contact head formed at the top with a concave seat, a conducting ball adapted to rest in said seat, and a helical contact spring in the casing attached at its upper end to the first named binding post and adapted to bear at its lower end upon said ball to yieldingly hold the

latter in said seat and thereby provide an electrical connection between said binding posts until the ball is jarred from between the contact head and the contact spring by violent impact of the vehicle with an object or another vehicle, said conducting ball being of a diameter to pass into the space in the casing about the contact head of the second binding post and to rest on the closure cap entirely below the contact spring.
